UNITED STATES PATENT OFFICE.

JAMES C. MENDEL, OF TITUSVILLE, FLORIDA.

FEED AND MEDICAMENT TROUGH.

1,220,441.

Specification of Letters Patent. Patented Mar. 27, 1917.

Application filed April 5, 1916. Serial No. 89,155.

To all whom it may concern:

Be it known that I, JAMES C. MENDEL, a citizen of the United States, residing at Titusville, in the county of Brevard and 5 State of Florida, have invented certain new and useful Improvements in Feed and Medicament Troughs, of which the following is a specification.

This invention relates to an improved 10 trough which is used for holding feed and medicament, the feed acting as a baif so that chickens will step into the medicament trough and thus have their feet and legs covered with the liquid medicament while 15 eating from the feed trough. This device is particularly adapted for curing what is known as "scaly legs," coal oil being placed in the trough together with water so that while the chickens are eating from the feed 20 trough, the oil will be applied to the legs.

Another object of the invention is to so construct this trough that the covers for the liquid troughs can be closed when it is not desired to use the device as a medicament 25 trough and may be swung open when so desired thus providing gang-ways leading to the medicament trough.

This invention is illustrated in the accompanying drawings, wherein:—

30 Figure 1 is a perspective view of the improved feed and medicament troughs.

Fig. 2 is a longitudinal vertical sectional view through the feed and medicament troughs.

35 The medicament trough 10 is provided with covers 11 which are hinged to the trough as shown at 12 and provided with strips 13 permitting the chickens to easily walk up the covers when swung to the position shown in Fig. 1. The feed trough 14 is provided with openings 15 through which access may be had to the interior of the feed trough and is provided with end flanges 16 for releasably holding closures 17 in place.

40 Brackets 18 are connected with the feed trough and secured to the side walls of the medicament trough 10 by means of rivets 19

thus firmly holding the feed trough in engagement with the walls of the medicament trough.

When this device is in use, water is placed 50 in the medicament trough and coal oil is then poured upon the water. Feed of some type is placed in the feed trough and the device is then ready for use. The covers 11 55 are turned back to the position shown in Fig. 1 thus forming gang-ways up which the chickens may easily walk. Upon reaching the medicament trough 10, the chickens will hop down into the trough in 60 order to reach the feed in the feed trough 14 and in doing so, will get the feet and legs covered with the coal oil. This coal oil is a very good cure for what is known as "scaly 65 legs" and it will thus be seen that with this 70 device, the coal oil can be applied to the chickens' legs without it being necessary to catch and hold the chickens while applying the coal oil. If it is desired to simply use the device as a feed trough, the covers 11 75 can be closed. It is obvious that any other type of medicament could be placed in trough 10.

What is claimed is:—

1. A device of the character described 75 comprising a base forming a receptacle, a trough extending across said base intermediate its length, and covers for the space between said trough and the ends of said base serving as gang-ways when moved to an 80 open position.

2. A device of the character described comprising a base, a trough extending across the base and having its walls provided with inlet openings, flanges carried by said 85 trough, and removable closures releasably held in a position to cover the inlet openings by said flanges.

In testimony whereof I affix my signature in presence of two witnesses.

JAMES C. MENDEL.
